[57] CLAIM

The ornamental design for an infant carrier, as shown and described.

DESCRIPTION

FIG. 1 is a perspective view of an infant carrier showing my new design;

FIG. 2 is a rear perspective view thereof with the straps unfastened from the fastening rings;

FIG. 3 is a reduced scale plan view of the exterior side of the infant carrier in an extended and flattened condition;

FIG. 4 is a plan view thereof showing the interior side with portions of the front straps being broken away for convenience of illustration.

The partial showing of surface shading indicating a fabric texture is understood to be continuous throughout on those surfaces where shown.
